UNITED STATES PATENT OFFICE.

SAMUEL H. BRECHEEN, OF PROSPER, TEXAS.

HARNESS.

1,265,040.

Specification of Letters Patent.

Patented May 7, 1918.

Application filed April 7, 1916. Serial No. 89,538.

To all whom it may concern:

Be it known that I, SAMUEL H. BRECHEEN, a citizen of the United States, residing at Prosper, in the county of Collin and State of Texas, have invented certain new and useful Improvements in Harness, of which the following is a specification.

My invention has relation to an improvement in the reinforcing of such portions of harness as are subjected to strain or undue abrasion such for instance as hame tugs, breech bands or the like and in such connection it relates more particularly to a composite structure wherein a metal chain is inclosed, the chain taking up or receiving the strain, the composite structure being used to protect the horse from contact with the chain and to prevent the chain from becoming knotted or tangled.

Inasmuch as leather has become relatively scarce and at its best readily splits when rotted, it has become necessary to provide in harness some substitute partaking of the nature of leather and yet stronger and not so expensive and yet more durable.

In the carrying out of my invention, the chain is inclosed between a relatively wide backing strap of stiff composite material such for instance rubber covered fabric and a relatively narrow facing strap of leather or pliable material, the two straps being stitched together along the upper and lower edges of the facing strap. The chain is not secured to either strap but is permitted slight play in the composite structure.

The nature and scope of my invention will be more fully understood from the following description taken in connection with the accompanying drawings forming a part hereof, in which—

Figure 1, is a front elevational view partly broken away of a hame tug embodying the main features of my invention.

Fig. 2, is a perspective view of a portion of said hame tug and

Fig. 3, is a perspective view of a breech band embodying my invention.

Referring to the drawings, 1 represents a chain constituting in Figs. 1 and 2 the tug.

The chain 1 is inclosed between a backing strap 2 of relatively non-pliable material such as rubber and fabric composite material and a facing strap 3 of leather or other pliable material. The backing strap 2 is relatively wide—much wider than the chain 1 and the facing strap 3 is relatively narrow—not much wider than chain 1 and the straps 2 and 3 are united by rows of stitches 4 arranged along the upper and lower edges of the facing strap 3.

In Fig. 3 the chain 11 constituting the breech is inclosed between a backing strap 12 of composite, non-pliable material constituting the breech band and a facing strap 13 of pliable material. In either form of my invention the chain is free to move longitudinally in the composite structure 2 and 3 but not to twist or buckle therein. In the breech band, the chain 11 is directly connected by straps 14 to the other parts of the harness.

Having thus described the nature and objects of my invention what I claim as new and desire to secure by Letters Patent is,—

1. In a harness, a relatively wide backing strap of stiff composite material, a relatively narrow facing strap of leather, and a chain inclosed between the straps and free to move therein, said straps being stitched together along the upper and lower edge of the narrow strap.

2. In a harness, a breech band, comprising a chain, supporting straps secured directly to the chain and connecting said chain with the harness, a relatively wide backing strap of stiff composite material, a relatively narrow facing strap of leather and a chain inclosed between the straps and free to move therein, said straps being stitched together along the upper and lower edge of the narrow strap.

In testimony whereof I have signed my name to this specification in the presence of two subscribing witnesses.

SAMUEL H. BRECHEEN.

Witnesses:

A. M. BATES,

A. W. JAMISON.
